UNITED STATES PATENT OFFICE.

JEROME BONITO, OF NEW YORK, N. Y.

SWIMMER'S FOOT-PADDLE.

1,098,471.

Specification of Letters Patent.

Patented June 2, 1914.

Application filed May 2, 1913. Serial No. 765,122.

To all whom it may concern:

Be it known that I, JEROME BONITO, a citizen of the United States, residing at New York city, in the county of New York 5 and State of New York, have invented certain new and useful Improvements in Swimmers' Foot-Paddles; and I do hereby declare the following to be a full, clear, and exact description of the invention, such as 10 will enable others skilled in the art to which it appertains to make and use the same.

This invention relates to new and useful improvements in artificial propelling devices for swimmers, and as its principal object contemplates the provision of a foot paddle which may be worn on the swimmer's ankle and will operate to give the drive of the swimmer's legs a greater bearing surface in the water.

20 The above and additional objects are accomplished by such means as are illustrated in the accompanying drawings, described in the following specification and then more particularly pointed out in the claim which 25 is appended hereto and forms a part of this application.

With reference to the drawings, wherein I have illustrated the preferred embodiment of my invention as it is reduced to practice, 30 and throughout the several views of which similar reference numerals designate corresponding parts: Figure 1 is a front elevation illustrating the foot paddle as it is applied to the swimmer's ankle; and Fig. 2 is 35 a section on the line 2—2 of Fig. 1.

Proceeding now to the description of the drawings, the numeral 1 designates the body portion of the paddle which is preferably formed of any suitable type of light sheet 40 metal, and is substantially V-shaped. The edges of the member 1 are rolled or turned, as at 2, to prevent the paddle from sliding through the water on the working stroke. The member 1 is riveted or otherwise se- 45 cured, as at 3, to a Y-shaped reinforcing rib 4, the longer leg of which projects beyond the apex portion of the paddle, as at 5, and is pivoted by means of a pin 6 between a pair of spaced perforated ears 7 and 8, 50 formed integral with and projecting laterally from a base plate 9. The plate 9 is bolted or riveted, as at 10, to an ankle strap 11, which is provided with the buckle 12 of any suitable or desired design. The termi- 55 nal 5 of the member 4 is enlarged as at 13,

being rounded on its lower face, and flattened on its edge face as at 14. An expansive helical spring 15 is secured at one terminal to the plate 9, and is fixed at its other terminal in any suitable manner to the adjacent face of the paddle 1. The spring 15 is designed to normally hold the member 1 at an approximate angle of thirty degrees to the face of the member 9, as will be observed by reference to Fig. 2.

In operation the ankle strap 11 is buckled on the ankle of the wearer and, when the leg is drawn forward, the member 1 swings on its pivot 6 in the direction of the plate 9 against the tension of the spring 15. Immediately upon the start of the working stroke of the swimmer's leg, however, the member 1 swings into a position of lateral extension to the plate 9, as indicated by dotted lines in Fig. 2. It will be observed that the swimmer thus attains a greater purchase on the water. It is to be observed in this connection that when the member 1 is in a position of lateral extension with respect to the base of the plate 9, the flat face 14 of the member 5 abuts the adjacent face of the member 9, thus acting as a stop for limiting the swinging movement of the paddle.

In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion and arrangement of parts may be resorted to, when required, without 95 sacrificing any of the advantages of my invention, as defined in the appended claim.

What I claim is:

A swimmer's foot paddle comprising an ankle strap, a base plate secured to the ankle strap, a pair of spaced ears formed on the base plate centrally thereof, a substantially V-shaped paddle member, a Y-shaped reinforcing and securing rib secured to said paddle member, an angular ear formed on said rib and pivoted between the spaced ears on the base plate, said angular ear being adapted to limit the movement of the paddle to a position of horizontal extension relative to the base plate, said paddle mem- 110

ber having its edges curved at approximately right angles to the body portion thereof, and a helical spring secured to the base plate and the paddle for normally holding the paddle in angular relation to the base plate and for returning the paddle to its normal position.

In testimony whereof I affix my signature in presence of two witnesses.

JEROME BONITO.
